UNITED STATES PATENT OFFICE.

FRANCIS P. MCCOLL, OF EASTPORT, MAINE, ASSIGNOR TO AMERICAN KEY CAN COMPANY, OF CHICAGO, ILLINOIS, A CORPORATION OF NEW JERSEY.

ROLL-TOP RECEPTACLE.

1,159,514.

Specification of Letters Patent.

Patented Nov. 9, 1915.

Application filed January 31, 1910. Serial No. 540,956.

To all whom it may concern:

Be it known that I, FRANCIS P. McCOLL, a citizen of the United States, residing at Eastport, county of Washington, State of Maine, have invented a certain new and useful Improvement in Roll-Top Receptacles, and declare the following to be a full, clear, and exact description of the same, such as will enable others skilled in the art 10 to which it pertains to make and use the same, reference being had to the accompanying drawings, which form a part of this specification.

My invention has for its object to produce 15 a simple and novel roll-top can or receptacle.

As subsidiary to the main object my invention has for a further object the production of a roll-top can having a joint between the roll-top and the can body which will 20 not be injured under the conditions to which it may be subjected during the "processing" of the contents of the can.

A further object subsidiary to the main object is to produce a roll-top can so formed 25 as to effect a considerable saving of stock over the constructions now in use.

A further subsidiary object of my invention is to provide means for facilitating the breaking of a soldered joint.

30 The usual form of roll-top can for containing and preserving food commodities is that wherein the cover is soldered to a flange projecting laterally from and surrounding one end of the can body; the cover being 35 provided with a tongue which may be received in a suitable key whereby, upon turning the key, first the tongue and then the cover itself is rolled up on the key so that the cover may be entirely removed. Most 40 food products must be "processed", that is cooked at least partially after they have been placed in the cans and the cans sealed. It will be seen that when heat is applied to such a sealed, filled can, a fluid pressure 45 is created which tends to move the soldered end of the can bodily in the outward direction. This strain imposed upon the soldered end must be borne by the line of solder nearest the interior of the can and, if the 50 pressure be great enough, the solder will yield and the strain will be transferred to a point a little farther out along the flange. The strain is therefore progressively carried outwardly along the flange as the separation

of the cover continues, no aid being given 55 to any portion of the joint by those portions which surround it and the strength of the joint being simply that of an extremely narrow annular ring. Therefore increasing the width of the joint by making 60 the flange upon which the cover is soldered wider does not add proportionately, if at all, to the resisting power of the joint when the cover is subjected to pressure from within. Solderers can be made strong enough 65 to withstand "processing" at low temperatures, but the limits of strength of a soldered joint are soon reached and, where high temperatures are needed, as in the case of meats, a very large percentage of roll-top ends of the character described will 70 yield and produce leaks.

In accordance with my invention I make the joint between the roll-top and the can body in such a manner that resistance to 75 separation while under internal pressure is exerted by the entire joint so that it is not necessary for one portion of the joint to yield before the holding effort of the adjacent portions come into play. To this end 80 I make the roll top in the form of a cup-shaped head the sides of which are in the form of a simple narrow flange which is soldered to the interior of the can body. This joint, because of its very capacity for 85 withstanding pressure in the interior of the can makes the rolling of the top from the can correspondingly difficult unless some special provision is made for facilitating the disruption of the joints, and I therefore 90 make such special provision.

The various features of novelty whereby my invention is characterized will herein-after be pointed out with particularity in the claims; but for a full understanding of 95 my invention and of its various objects and advantages, reference may be had to the following detailed description taken in connection with the accompanying drawings, wherein:

Figure 1, is a top view of a round can embodying my invention; Fig. 2, is an enlarged section on line 2-2 of Fig. 1; Fig. 3 is a side view of the head or cover; Fig. 4 is a section similar to Fig. 2, on a still larger 105 scale, showing only a fragment of the upper end of the can and cover; Fig. 5 is a view similar to Fig. 4, showing the beginning of

the rolling operation; Fig. 6 is a section on line 6—6 of Fig. 4; Fig. 7 is a view similar to Fig. 1 showing a slight modification; Fig. 8 is a plan view of a rectangular can; Fig. 9 is an enlarged section of the can shown in Fig. 8, the cover or head being shown in side elevation; Fig. 10 is a view, on an enlarged scale, looking in the direction of the arrow marked X in Fig. 8; Fig. 11 is a plan view of a can having an inserted key and containing one feature of my invention; Fig. 12 is a section on line 12—12 of Fig. 11; Fig. 13 is a section on line 13—13 of Fig. 12; and Fig. 14 is a view similar to Fig. 13, showing a further modification.

In the first seven figures I have illustrated my invention as applied to a cylindrical can, the body of the can being in the form 20 of a cylindrical tube A. The roll-top consists of a head B and a narrow annular flange C which gives to the top the appearance of a shallow cup.

D is the usual key-receiving tongue which, 25 in this instance, projects from the free edge of the flange. The parts are so proportioned that the flange fits within the end of the can and are so assembled that the flange is directed outwardly, its outer edge lying 30 approximately flush with the outer edge of the can body. It will be seen that when a key is applied to the tongue so as to roll it up, a substantially longitudinal pull will be exerted upon the joint directly beneath 35 the tongue so that considerable power must be exerted before the joint will give way. I have found that if the vertical flange is made deep enough to insure positively against leakage at the joint under "processing," it is almost impossible to break the joint by rolling up the top and I have therefore constructed the parts so that the joint offers a minimum resistance to tearing adjacent to the tongue when the tongue is 40 rolled up on a key; thus making it possible to break the joint at this point and start the rolling of the top. To this end I construct the parts so that the depth of the joint, measured lengthwise of the can, is decreased 45 in any suitable manner adjacent to the tongue or other starting means; this being preferably accomplished by making the band of solder narrower at this point than at certain other points. One of the simplest ways 50 of narrowing the soldered joint is by making the flange directly adjacent to the tongue as shallow as possible, as indicated at c, without weakening the joint so as to endanger its tightness at this point under internal pressure. I have found that this may 55 be done without in any way endangering the tightness of the joint when the can is subjected to the "processing" operation because the remainder of the flange may be 60 made as deep as desired and so support the 65

portion of the joint adjacent to the tongue. The greater depth of the flange at points removed from the tongue does not interfere materially with the disrupting of the joint during the rolling operation of the top since 70 the disruption is comparatively easy after it has once been started. The base of the tongue must be made comparatively wide in all roll-top cans in order to give it sufficient strength to start the tearing of the 75 joint initially and, in the arrangement illustrated, the upper portion of the wall of the can body directly beneath the tongue will tend to yield under pressure and be flattened slightly so that the pull upon the 80 tongue must overcome the resistance of the entire length of that portion of the joint lying under the base of the tongue. This will not only make it difficult to start the tearing of the joint but it may result in tearing off the tongue or distorting the parts in such a way that un-rolling of the top becomes impossible. This objectionable condition may be avoided by providing some means which will cause the joint to be broken 85 first at a single point for, after a break has once occurred, the unrolling becomes comparatively easy. I have found that this problem may be solved by making a small laterally directed jog in the flange directly 90 beneath the tongue and preferably, although not necessarily at about the center line of the tongue. This jog may be effected in various ways, the simplest being to indent the flange slightly as indicated at c' at a 95 point beneath the tongue so as to provide a small outwardly extending tooth or projection at this point. When the top is placed in position in the end of the can and the soldering is done, the tooth or projection 100 on the top produces a slight indentation in the side of the can as at a. When the tongue is rolled upon a key the strain first comes upon that portion of the joint lying between the indentations a and c and, by making these small the tearing of the solder at this point will be easily affected. The indentation in the side wall of the can not only makes it possible to start the tearing 105 of the joint at a point instead of along a line, but it also stiffens the upper end of the can body in the transverse direction so that the tendency to flatten when the pressure is applied upon the tongue is obviated. 110

The feature of reducing the width of the flange at the point where the breaking of the joint is to begin and the feature of providing the jog in the joint, both have special advantages and either may be used under certain conditions without the other but, in the arrangement I have just described, it is better to combine the two since in this way it is possible to obtain a joint having a sufficient factor of safety without making the un-rolling of the top objec- 115 120 125 130 135

tionably difficult. The manner in which the lessening of the depth of the flange occurs may be varied, although it is preferable that the decrease in depth be gradual so that 5 there will be no abrupt step from a narrow portion to a wider one. In round cans the most difficulty in rolling the top is encountered during the first half or third of the 10 operation and therefore the best results will be obtained by gradually decreasing the depth of the flange from points diametrically opposed to each other or, if desired, a gradual decrease may take place in both directions from a point diametrically opposite 15 the tongue. If desired, more than one jog may be placed in the joint adjacent to the tongue as well as at other points along the joint. These jogs have an advantage wherever they are placed in that they make 20 it possible for the tearing of the joint to take a new start whenever the points at which the jogs are located are reached.

The upper edge of the flange is preferably, though not necessarily, provided with 25 a small out-turned fin c^2 which is preferably no wider than the thickness of the metal of which the can body is made. This fin serves not only to prevent the top from being forced too far into the end of the can but 30 also to facilitate the breaking of the joint by providing along the joint a small lateral extension which may easily be disrupted and thus make a start for the disrupting of the main portions of the joint lying directly beneath.

In Figs. 8 to 10 I have illustrated my invention as applied to a rectangular can, the tongue E being arranged at one corner of the top or cover F . In this instance the 40 flange G decreases gradually in depth as the tongue is approached along the two adjacent sides of the rectangle, as indicated at g . In this arrangement the depth of the flange may be decreased adjacent to each 45 of the other corners as indicated at g' in Fig. 9. The strongest parts of the joints under internal pressure are those adjacent to the corners and therefore the depth of the joint at these points may be lessened without 50 weakening the joint while at the same time facilitating the unrolling of the top. In this arrangement, as in the other, there may be a slight abrupt jog in the joint at a point beneath the tongue as at g^2 . The 55 flange is illustrated as being indented at a number of other points g^3 so as to provide jogs in the joint at these points also. As heretofore stated, these jogs may be placed wherever it is desired to permit the tearing 60 of the joint to take a new start, the locations of these jogs, if any are employed, depending upon the particular shape of the joint and being such as to permit a new start to be made wherever difficulty may be encountered 65 during un-rolling. Where there are

corners in the cover I prefer, at these points, to make the fin to which I have heretofore referred somewhat wider, as indicated at g^4 so as to insure against tearing of the flange at these points where the joint is always the 70 strongest.

It will now be seen that I have provided a simple and novel arrangement which permits the joint to lie at right angles to the plane of the joint ordinarily used in roll-top cans, therefore making the joint immeasurably stronger, under internal pressures in the can. By reason of the location of the joint it is unnecessary that its depth be made great because a comparatively narrow flange 75 will provide an ample factor of safety, consequently only a minimum amount of metal is required for the top or cover, all the metal ordinarily used to form the wide laterally projecting flange being saved. Another saving in metal occurs in the can body itself 80 because of the omission of the usual laterally projecting flange around the mouth of the can. This latter saving is of particular importance in drawn cans wherein the 85 sides and one end are made from a single piece which is pressed and drawn into the proper shape, the saving of metal by the omission of the lateral flange being an amount equal to a band or strip at least a 90 quarter of an inch wide extending circumferentially around the flat piece which is required for the can. It will therefore be seen that I have provided not only a can having 95 a much more effective joint than heretofore 100 employed but also one in which there is a considerable saving of material necessary for its construction. It will also be seen that the up-turned flange on the head strengthens 105 it at the edges so that the danger of tearing, which has heretofore been present in all roll-top cans, is entirely avoided. Furthermore, because of the stiffness of the head, the upper edge of the can is caused to be turned outwardly during the operation 110 of removing the cover, thus enlarging the mouth of the can and facilitating the discharge of its contents.

The placing of a jog in the joint is of advantage in another form of roll-top illustrated in Figs. 11 to 14: namely a roll-top having an inserted tongue. Referring to these latter figures, H represents the cover or side of a can having therein an elongated slit h . I is a tongue which lies on the outside 115 of the member H and has one end projecting through the slit and soldered to the under side of the member H on one side of the slit. The member H is weakened along a line indicated by the dotted line H' leading 120 from the ends of the slit. In this arrangement the key is applied to the tongue and that portion of the member H inclosed with in the weakened line and the slit is torn 125 away. It will be seen that when the tongue 130

is rolled upon the key, the first break must occur at some point along the soldered joint adjacent to the slit end, if the joint is tight, as it should be, it is very difficult to break it because the entire joint will offer resistance. Consequently there will be a yielding of the tin around the joint and perhaps a tear will occur at some point other than along the weakened line or along the joint. 5 A break in the joint itself may be assured by providing therein a jog similar to that heretofore described so as to make it possible for the pull of the tongue to be concentrated at one point instead of being distributed along the entire base of the tongue. 10 This may be accomplished by indenting the tongue longitudinally as indicated at i , this indentation preferably extending through the joint and into the free portion of the tongue. 15 When the tongue is rolled up a break will be caused at the point where the indented portion passes through the joint. If desired the tongue and the overlying portion of the cover may both be indented as 20 in the previous forms, thus providing a starting point for the tearing of the joint and at the same time stiffening the cover and forming a fulcrum about which the tongue may act. Such an arrangement is shown in 25 Fig. 14 the tongue being indicated at I' , the cover at H^2 , and the inter-locking indentations being indicated respectively, at i' and h^2 .

While I have illustrated and described 30 with particularity only certain preferred forms of my invention I do not desire to be limited to the particular details of construction and arrangement illustrated, but intend to cover all forms and arrangements falling 35 within the terms of the definitions of my invention constituting the appended claims.

What I claim is:

1. A can having a cup-shaped head fitting in one end thereof with its mouth directed 40 outwardly, the sides of the head being in the form of a flange engaging closely with the surrounding portion of the can, said flange having at the edge a fin whose width is approximately equal to the thickness of 45 the metal of the body of the can, a layer of solder lying between said flange and the surrounding portion of the can and forming a narrow annular joint whose width extends 50 lengthwise of the can, and means for rolling 55 said head up so as to remove it from the can.

2. A can having a cup-shaped head soldered into one end thereof with its mouth directed outwardly, the sides of the head being in the form of a flange adapted to fit 60 into the end of the can, a portion of said flange being shallower than the remainder, and means for rolling up said head from a point adjacent to the narrow portion of the flange.

3. A can having a cup-shaped head sol-

dered into one end thereof with its mouth directed outwardly, the sides of the head being in the form of a flange adapted to fit into the end of the can, and means for rolling up said head to remove it from the can, 70 said flange decreasing gradually in depth adjacent to said means.

4. A can having a cup-shaped head soldered into one end thereof with its mouth directed outwardly, the sides of the head 75 being in the form of a flange adapted to fit into the end of a can, said flange having a laterally extending projection forming a jog in the soldered joint, and means for rolling up said head from a point adjacent to 80 said projection to remove it from the can.

5. A can having a cup-shaped head soldered into one end thereof with its mouth directed outwardly, the sides of the head being in the form of a flange shaped to fit 85 into the can, and a tongue projecting from said head at one side thereof, the side of the can and the flange being indented at a point beneath the plane of said tongue.

6. A can having a cup-shaped head soldered into one end thereof with its mouth directed outwardly, the sides of the head being in the form of a flange adapted to fit into the end of the can, said flange having a laterally extending wedge-shaped projection 90 forming a jog in the soldered joint, and means for rolling up said head from a point adjacent to said projection so as to remove 95 it from the can.

7. A can having a cup-shaped head soldered into one end thereof with its mouth directed outwardly, the sides of the head being in the form of a flange adapted to fit into the end of the can, and means for rolling up the head to remove it from the can, 100 the flange and the adjacent portion of the can being abruptly indented at one or more points.

8. A can having a cup-shaped head soldered into one end thereof with its mouth directed outwardly, the sides of the head being in the form of a flange adapted to fit into the end of the can, and a tongue projecting from the free edge of the flange, the flange and the adjacent portion of the can 110 being abruptly indented at a point beneath 115 the plane of the tongue.

9. A can having a cup-shaped head soldered into one end thereof with its mouth directed outwardly, the sides of the head being in the form of a flange adapted to fit into the end of the can, and means for rolling up the head to remove it from the can, there being an abrupt jog in the soldered joint at one or more points.

10. A can having a cup-shaped head soldered into one end thereof with its mouth directed outwardly, the sides of the head being in the form of a flange adapted to fit into the end of the can, and a tongue pro-

jecting from the free edge of the flange, said flange being shallower at one or more points than the remainder of the flange.

11. In a can, two members soldered together, one of said members having a tongue projecting therefrom adjacent to the soldered joint for disrupting the joint, and there being an abrupt jog in said joint at the base of the projecting portion of the tongue.

10 12. In a can, two members soldered together, one of said members having a tongue projecting therefrom at the soldered joint for disrupting the same, and one of said members being indented at the point where

15 said tongue leaves the joint.

13. In a can, two members soldered together, one of said members including a tongue projecting therefrom adjacent to the soldered joint for disrupting the same, both 20 of said members being indented at a point in said joint nearest the base of the projecting portion of the tongue.

14. A can having a cup-shaped head soldered into one end thereof with its mouth 25 directed outwardly, the sides of the head

being in the form of a flange which fits into and is soldered to the interior of the can, the parts being so proportioned that the soldered joint measured lengthwise of the can is narrowed at one or more points, and 30 means for rolling up said head from a point adjacent to a narrow portion of the joint.

15. A can having a cup-shaped head soldered into one end thereof with its mouth directed outwardly, the sides of the head 35 being in the form of a flange fitting into and soldered to the interior of the can, and a tongue for rolling up said head from one side thereof, the parts being so proportioned and arranged that the joint offers less 40 resistance to disruption adjacent to said tongue upon rolling up the tongue than at certain other points.

In testimony whereof I sign this specification in the presence of two witnesses.

FRANCIS P. McCOLL.
